United States Patent Office

Des. 227,541
Patented July 3, 1973

227,541

BLENDER TOP OR SIMILAR ARTICLE

Mitchell A. Himmel, 1 Park Lane,
Mount Vernon, N.Y. 10552

Filed Jan. 25, 1971, Ser. No. 109,724

Term of patent 14 years

Int. Cl. D7—04

U.S. Cl. D7—154

FIG. 1

FIG. 2

FIG. 3

FIG. 1 is a side elevational view of the blender top embodying my new design and showing it with the head of the top projecting downwardly;

FIG. 2 is a bottom plan view thereof; and

FIG. 3 is a cross-sectional view thereof on an enlarged scale taken on line 3—3 of FIG. 1.

I claim:

The ornamental design for a blender top or similar article, substantially as shown.
